(57) **CLAIM**

The ornamental design for an operating device for ultrasonic control device, as shown and described.

DESCRIPTION

FIG. 1 is a top, front and right side perspective view of an operating device for ultrasonic control device showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a view of the operating device for ultrasonic control device in an environment of use; and,

FIG. 8 is a view of the operating device for ultrasonic control device in an environment of use.

The broken lines showing the portions of the operating device in FIGS. 3 and 4 are for illustrative purposes only and form no part of the claimed design.
